UNITED STATES PATENT OFFICE

2,253,349

CARPET SWEEPER

Fred W. Pullen, Grand Rapids, Mich., assignor to
Bissell Carpet Sweeper Company, Grand Rapids, Mich.

Application May 20, 1940, Serial No. 336,153

6 Claims. (Cl. 15—41)

This invention relates to improvements in carpet sweepers.

This invention relates to carpet sweepers and particularly to dust pan holding and dumping mechanisms.

It has for its objects:

First, to provide a simple and effective dust pan dumping mechanism for carpet sweepers which may be made inexpensively.

Second, to provide such a mechanism in which the dust pans are held resiliently in closed position to eliminate rattling thereof during operation of the sweeper.

Third, to provide such a mechanism in which the pans may be easily dumped by merely releasing the mechanism without the necessity for exerting a force on the pans for this purpose and which cannot be injured when the pans are open if the sweeper is inadvertently placed on the floor and which cannot be injured even if the pans are moved to open position momentarily without releasing the releasable portion of the mechanism.

Other objects and advantages pertaining to details and economies of construction and operation will appear from the description to follow. The invention is defined in the claims. A preferred embodiment of my invention is illustrated in the accompanying drawing, in which:

Fig. 1 is a sectional view through a carpet sweeper embodying my invention.

Fig. 2 is a view showing the parts employed in my invention in disassembled relationship.

Fig. 3 is a partial sectional view showing one of the pans opened manually and the action of the mechanism when this is done.

The carpet sweeper 1 has a case 2 having a top 3, ends 4 and sides 5. The sides are wood pieces which extend lengthwise of the case and are notched at the bottom at 6 to provide stops against which the pans 7 of the carpet sweeper close. Suitable wheels 8 and a brush 9 are also provided.

The dust pans 7 extend lengthwise of the case and are spaced from one another, one pan extending along each side of the bottom of the case to close the same. Adjacent the ends of the inner edges of the pans are ears 10 which are apertured to receive pivot screws 11 on the end of the case. The pans pivoted on these pivot screws may be swung from closed position shown in full lines in Fig. 1 to an open position indicated by dotted lines at the right in Fig. 1. For actuating the pans for dumping them and for holding them resiliently in closed position,

I provide pan closing means 12 consisting of a spring which has its ends 13 pivoted in the ends of the pans at points spaced outwardly toward the edges of the case from the pivot screws 11.

5 The pan closing means 12 has a central straight horizontal portion 14.

The spring means 12 because of the shape thereof has sufficient resiliency to permit the spring to flex somewhat as the pans move from open to closed position, so that when the pans are held in closed position the resiliency of the spring means 12 holds them resiliently to eliminate rattling.

On the end of the case adjacent the spring means 12, I provide a spring wire dump lever 15 having central pivot portion 16 and an inner arm 17 and an outer arm 18 which are offset from one another. This dump lever is pivoted in an aperture 19 in the case in which I provide a U-shaped bearing member 20 which is formed of suitable sheet metal. At the inner end of the arm 17, I provide a loop 171 in the wire through which the straight horizontal portion 14 of the spring means 12 extends slidably. At the outer end of the dump lever 15, I form a loop or eye 21 in which a rivet 22 is inserted to provide a suitable pressure plate for the exertion of pressure by the finger of the operator of the sweeper.

On the case I provide a catch 23 under which 30 the outer end of the lever 15 may be engaged when the pans are in closed position, so that they will be held in closed position. When the sweeper is closed, the spring dump lever 15 is slightly tensioned and its tension assists the spring means 12 in exerting a resilient force to hold the pans in closed position.

When it is desired to dump the dust pans, a slight pressure on the lever 15 and an outward movement away from the catch 23 releases the lever, permitting it to swing upwardly. This permits the dust pan to swing downwardly so that litter collected in the use of the sweeper may be dumped. The spring means exerts substantially no pan closing tension when the lever is released and the pans fall freely to dumping position.

By providing the loop 18 through which the horizontal portion 14 of the spring means 12 may 50 slide, I eliminate danger of injury to the mechanism which might result if the sweeper were put down with the pans in open position. If this were done, one of the pans would be bent back around under the brush and if this is done the horizontal portion 14 of the spring means 12 will

slide through loop 18 so that no permanent set in the spring means 12 results.

Many times those conversant with carpet sweepers will grasp the pans and open them manually. With a mechanism of the type shown and described, injury might result to the pan spring if this were done without releasing the lever 15 from the catch 23, were it not for the fact that when this is done with the carpet sweeper above described, the spring lever will flex, as shown in Fig. 3, sufficiently to avoid putting a permanent set in the pan closing spring means 12.

The terms and expressions which have been herein employed are used as terms of description and not of limitation and there is no intention in the use of such terms and expressions of excluding any equivalents of the features shown and described. It is recognized that various modifications are possible within the scope of the invention claimed.

Having thus described my invention, what I claim as new and desire to secure by Letters Patent is:

1. In a carpet sweeper having a case, the combination of a pair of spaced dust pans each extending along one side of the bottom of the case to close the same, stops on the case against which the pans rest in closed position, pivots on said case pivoting said pans adjacent the ends of their inner edges to permit the pans to swing downwardly from the bottom of the case, spring means having its ends pivoted to the ends of the pans at points spaced from the aforesaid pivots outwardly toward the edges of the case and having a substantially straight central horizontal portion, a spring wire dump lever having a centrally located pivot portion and offset arms extending from opposite ends thereof with its pivot portion pivoted in an aperture in the end of the case, the inner end of said lever having a loop formed therein through which the central portion of said spring means extends slideably, and a catch on said case to engage the outer end of said lever and hold it in down position to hold the pans closed resiliently against said stops, said spring means being so disposed that on release of said lever said spring means exerts substantially no pan closing tension, whereby the release of said lever permits the free end thereof to raise and said pans to swing downwardly free from pan closing spring tension to dump the sweeper.

2. In a carpet sweeper having a case, the combination of a pair of spaced dust pans each extending along one side of the bottom of the case to close the same, stops on the case against which the pans rest in closed position, pivots on said case pivoting said pans adjacent the ends of their inner edges to permit the pans to swing downwardly from the bottom of the case, spring means having its ends pivoted to the ends of the pans at points spaced from the aforesaid pivots outwardly toward the edges of the case and having a substantially straight central horizontal portion, a spring dump lever pivoted between its ends on the end of said case and having its end slideably engaging the central portion of said spring means, and a catch on said case to engage the outer end of said lever and hold it in down position to hold the pans closed resiliently against said stops, said spring means being so disposed that on release of said lever said spring means exerts substantially no pan closing tension, whereby the release of said lever permits the free end thereof to raise and said pans to

swing downwardly free from pan closing spring tension to dump the sweeper.

3. In a carpet sweeper having a case, the combination of a pair of spaced dust pans each extending along one side of the bottom of the case to close the same, stops on the case against which the pans rest in closed position, pivots on said case pivoting said pans adjacent the ends of their inner edges to permit the pans to swing downwardly from the bottom of the case, spring means having its ends pivoted to the ends of the pans at points spaced from the aforesaid pivots outwardly toward the edges of the case, a spring dump lever pivoted between its ends on the end of said case and having resiliency in its plane of pivotal movement and having its inner end engaging said spring means, and a catch on said case to engage the outer end of said lever and hold it in tension and in down position to hold the pans closed resiliently against said stops, said spring means being so disposed that on release of said lever said spring means exerts substantially no pan closing tension, whereby the release of said lever permits the free end thereof to raise and said pans to swing downwardly free from pan closing spring tension to dump the sweeper.

4. In a carpet sweeper having a case, the combination of a pair of spaced dust pans each extending along one side of the bottom of the case to close the same, stops on the case against which the pans rest in closed position, pivots on said case pivoting said pans adjacent the ends of their inner edges to permit the pans to swing downwardly from the bottom of the case, a pan closing member having its ends pivoted to the ends of the pans at points spaced from the adjacent pivots outwardly toward the edges of the case and extending between the pans and having a substantially straight central horizontal portion, a spring wire dump lever having a centrally located pivot portion and offset arms extending from opposite ends thereof with its pivot portion pivoted in an aperture in the end of the case, the inner end of said lever having a loop formed therein through which the central portion of said pan closing member extends slideably, and a catch on said case to engage the outer end of said lever and hold it in down position to hold the pans closed resiliently against said stops.

5. In a carpet sweeper having a case, the combination of a pair of spaced dust pans each extending along one side of the bottom of the case to close the same, stops on the case against which the pans rest in closed position, pivots on said case pivoting said pans adjacent the ends of their inner edges to permit the pans to swing downwardly from the bottom of the case, a pan closing member having its ends pivoted to the ends of the pans at points spaced from the adjacent pivots outwardly toward the edges of the case and extending between the pans and having a substantially straight central horizontal portion, a spring dump lever pivoted between its ends on the end of the case and having its inner end slideably engaging the central portion of said pan closing member, and a catch on said case to engage the outer end of said lever and hold it in down position to hold the pans closed resiliently against said stops.

6. In a carpet sweeper having a case, the combination of a pair of spaced dust pans each extending along one side of the bottom of the case to close the same, stops on the case against which

the pans rest in closed position, pivots on said case pivoting said pans adjacent the ends of their inner edges to permit the pans to swing downwardly from the bottom of the case, pan closing means pivoted to the ends of the pans at points spaced from the adjacent pivots outwardly toward the edges of the case and extending between the pans, a spring dump lever pivoted between its ends on the end of the case and

5 having resiliency in its plane of pivotal movement and having its inner end engaging said pan closing means, and a catch on said case to engage the outer end of said lever and hold it in tension and in down position to hold the pans closed resiliently against said stops.

FRED W. PULLEN.
